DESIGN FOR A POWER TOOL UNIT

Theodore S. Briskin, Chicago, Ill., assignor to Excel Auto Radiator Company, Chicago, Ill., a corporation of Delaware

Application November 20, 1944, Serial No. 116,597

Term of patent 7 years

(Cl. D54—14)

To all whom it may concern:

Be it known that I, Theodore S. Briskin, a citizen of the United States and a resident of Chicago, in the county of Cook and State of Illinois, have invented a certain new, original, and ornamental Design for a Power Tool Unit, of which the following is a specification, reference being had to the accompanying drawings, forming part thereof, in which—

Fig. 1 is a view taken from the chuck end of a power tool unit showing my new design;

Fig. 2 is a side elevational view thereof;
Fig. 3 is a top plan view thereof;
Fig. 4 is a view of the opposite side of Fig. 2;
and

Fig. 5 is a view of the opposite end of Fig. 1.

I claim:

The ornamental design for a power tool unit, as shown.

THEODORE S. BRISKIN.
